US00D991595S

(12) **United States Design Patent** (10) Patent No.: **US D991,595 S**
So (45) Date of Patent: ** Jul. 4, 2023

(54) **ULTRASONIC DOG TRAINER**

(71) Applicant: **BONSO TECHNOLOGY (SHENZHEN) CO., LTD.**, Shenzhen (CN)

(72) Inventor: **Chun Bong So**, Shenzhen (CN)

(73) Assignee: **BONSO TECHNOLOGY (SHENZHEN) CO., LTD.**, Shenzhen (CN)

(**) Term: **15 Years**

(21) Appl. No.: **29/807,669**

(22) Filed: **Sep. 14, 2021**

(30) **Foreign Application Priority Data**

Aug. 20, 2021 (CN) 202130545336.7

(51) **LOC (14) Cl.** **30-99**

(52) **U.S. Cl.**

USPC **D30/199; D10/104.1**

(58) **Field of Classification Search**

USPC D30/151-155, 144, 199, 160; 119/792-798, 850, 855-859, 654, 905, 119/907, 815, 712, 802, 784, 769, 760, 119/776, 862, 908, 860, 719-721; 242/381.1-381.2, 385.4, 378.3, 376.1, 242/385.1, 916, 601, 570, 405, 404, 371, 242/223, 170, 388.1, 405.2, 377, 381.3, 242/381.6, 405.3, 388, 6, 384.7, 382, 242/396.1, 404.1, 380; 362/108; 33/767, 33/769, 414; D12/400; D3/229, 230, D3/207, 208, 215; 40/1.5, 455, 640, 303; 206/63.3, 459.5, 702, 408; D6/515; D8/358, 360, 347, 360.1, 359, 356, D8/DIG. 1; D24/145, 167, 186, 146, 169; D10/57, 72, 106.1, 104.1, 104.2, 109.2; D10/70, 97, 98, 78, 65; D20/28; 224/666, 678; 16/445; 283/74, 70;

(56)

D11/232, 200, 216, 1, 2, 86, 87, 201, D11/206-210, 212-215, 218; 24/163 K, 24/122.3, 323, 702, 600.4-600.7, 163 R, 24/169-171, 173, 177-179, 191, 194, 24/195, 197, 200, 303, 616, 635, 313, 24/615, 3, 6, 3 K, 599.2, 96, 221, 237, 24/311, 312, 314, 321, 338, 339, 309; 428/3, 4; 54/76, 1, 71; 63/29.1, 3; 191/12.2 R, 12.4; D13/154, 153, 137.4, (Continued)

(57) **CLAIM**

The ornamental design for an ultrasonic dog trainer, as shown and described.

DESCRIPTION

FIG. 1 is a perspective view of an ultrasonic dog trainer, showing my new design;

FIG. 2 is a perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof; and,

FIG. 9 is an enlargement detail view of FIG. 1.

The broken lines shown depict unclaimed features of the ultrasonic dog trainer and form no part of the claimed design.

1 Claim, 9 Drawing Sheets
